UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed December 22, 1917. Serial No. 208,443.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to automatic heel-building machines, and it has special reference to machines of this general class in which heel lifts are successively removed from a series of holders or magazines containing a supply of stacked lifts of graded characteristics and are progressively superposed the one upon the other in a predetermined sequence at successive assembling stations to produce heels of any desired form.

In a copending application, Serial No. 208,444, filed by me of even date herewith in which claims will be found dominating certain features of the present invention, an automatic heel-building or assembling machine is disclosed, a portion of which is particularly adapted to assemble a plurality of lifts of even or uniform thickness to form heels, or parts or sections of heels having parallel upper and lower surfaces. This machine, however, is incapable of building wedge heels, inasmuch as no provision is made to accommodate the wedge lifts which are utilized in such heels.

One of the objects of this invention, therefore, is to provide a machine which is peculiarly constructed and operated to automatically build heels in which wedge-lifts are employed.

In a more specific aspect, an object of the invention is to provide a machine for building wedge heels which is adapted to produce heel-piles having substantially plane breast surfaces that may be readily compressed into properly formed heel-blanks without the necessity of a preliminary breast trimming operation.

Another object of this invention is to provide a heel-building machine which shall embody picker members for transferring the lifts from the magazines to the assembling stations, that shall act upon the lifts in such manner as to avoid mutilating, deforming

or otherwise injuring even thin lifts of soft material, and, moreover, shall be capable of picking up, one at a time, lifts of various forms and conditions, such as extremely thin skived lifts and lifts having relatively large central openings, that cannot be successfully handled by the pronged or claw picker members of the prior art which penetrate the central portion of the lifts acted upon.

Still further objects are to simplify and improve the construction and operation of automatic heel-building machines, and to provide a machine of this class which shall be relatively simple and compact in arrangement, and reliable, effective, and expeditious in operation.

In accordance with the preferred embodiment of the invention, the above-mentioned objects are accomplished by means of a machine which embodies a plurality of concurrently operative picker members that are intermittently swung back and forth between a row of magazines or lift holders, in which a supply of lifts of graded characteristics are stacked, and a plurality of assembling stations that are occupied by independent intermittently movable carriers, upon which the lifts are superposed in a predetermined sequence to form heels.

One feature of the invention resides in the combination of a picker member for seizing lifts and a lift magazine in which wedge-lifts are alternately or reversely stacked and which is rotated through a half turn just prior to each transfer of lifts by the picker member, whereby the wedge-lifts occupy similar positions in the magazine at the time they are removed by the picker member.

Another feature of the invention is the provision of means for properly inclining or tilting each carrier in its wedge-lift assembling station just before the wedge-lift is placed thereon in order to maintain the upper surface of the assembled lifts in a horizontal plane. In conjunction with this means for tilting the carriers, cooperating means is provided for advancing or feeding each carrier into its wedge-lift, and all subsequent lift assembling stations, a slightly shorter distance than into the preceding station. Thus, the breast edges of all of the component lifts are aligned in a substantially plane surface, the only projecting portion being a slight angular projection ef-

60

70

90

100

105

110

fected by the tilting of the lowermost lift. This portion is relatively small and the heel-piles, therefore, may be compressed, without checking, distortion and relative 5 shifting of the component lifts, into substantially regular and perfect heel blanks.

A further feature of the invention resides in the use of picker members that are periodically coated with paste and to which 10 the uppermost lifts in the magazine adhere during the transferal of lifts to the assembling stations. Thus, lifts of any form and condition may be picked up one at a time and without injury or mutilation, while the 15 paste which has been applied to the lifts by the pickers serves as a binder to unite the superposed lifts into solid heels.

Other objects and features of the invention will be readily apparent to those skilled 20 in the art from the drawings and the following detailed description of the preferred embodiment. Obviously, the invention is not restricted to the construction, arrangement and location of parts and operation 25 set forth, and many modifications may be made therein without departing from the spirit and scope thereof.

Furthermore, the invention as herein set forth, is not limited to the conjoint use of 30 all its features, and it will be understood from the following description that it is within the scope of the invention to use some features without others or to combine the various features in a different manner 35 than is described as the preferred combination. Therefore, only such limitations should be imposed as are indicated in the appended claims.

The preferred embodiment of the invention is illustrated in the accompanying drawings, in which, Figure 1 is a view in side elevation of a machine constructed in accordance with the invention, a side supporting pedestal being removed for the sake 40 of clearness; Fig. 2 is a plan view of the machine; Fig. 3 is a view, partially in side elevation and partially in section, of the machine shown in Figs. 1 and 2, the section being taken on the line 3—3 of Fig. 2; Fig. 45 is an enlarged plan view, partially in section, of a rotatable wedge lift holder or magazine, the section being taken on the line 4—4 of Fig. 6; Fig. 5 is an enlarged sectional elevation of the wedge lift holder shown in Fig. 4, the section being taken on the line 5—5 thereof; Fig. 6 is an enlarged sectional view of the wedge lift holder shown in Figs. 4 and 5, the section being taken on the line 6—6 of Fig. 4; Fig. 7 is 55 an enlarged sectional view similar to Fig. 4 showing the adjustable parts of the lift holder in their outermost position, the section being taken on the line 7—7 of Fig. 5; Fig. 60 is an enlarged sectional view similar to Fig. 4 showing the adjustable parts of the lift holder in their outermost position, the section being taken on the line 7—7 of Fig. 5; Fig. 8 is an enlarged side elevation of a finished 65 heel-pile produced by the machine in posi-

tion upon one of the movable carriers upon which it is assembled; Fig. 9 is an enlarged plan view of a portion of the machine showing particularly the rotatable wedge-lift holder and its actuating means; Fig. 10 is 70 an enlarged view, partially in elevation and partially in section, of a portion of the machine showing the lift holders or magazines and the pasting apparatus, the section being taken on the line 10—10 of Fig. 2; Fig. 11 75 is an enlarged plan view, partially in section on the line 11—11 of Fig. 12, of the clutch for operating the rotatable wedge lift holder; Fig. 12 is an enlarged view, partially in section and partially in side elevation, of 80 the mechanism shown in Fig. 11; Fig. 13 is an enlarged view, partially in section and partially in side elevation, of a portion of the tracks for guiding and supporting the movable carriers upon which the lifts are 85 assembled; Fig. 14 is an enlarged view, partially in elevation and partially in section, of a portion of the machine illustrating certain of the movable carriers supported on their tracks in the first and second assem- 90 bling station; Fig. 15 is an enlarged perspective view, partially in section, of a portion of the carriers, supporting tracks, and intermittent carrier-feed mechanism; Fig. 16 is a perspective view of one of the mov- 95 able lift carriers, showing the chain conveyor and means for engaging the carrier; Fig. 17 is an enlarged plan view of a portion of the machine, showing the swinging picker members in their positions above and 100 in engagement with the paste roll; Fig. 18 is an enlarged plan view of a portion of the machine showing the swinging picker members in position above the lift holders or magazines; and Fig. 19 is an enlarged view, 105 partially in section and partially in end elevation, of a portion of the machine, the section being taken along the line 19—19 of Fig. 2.

Referring to the drawings, and particu- 110 larly to Figs. 1, 2 and 3, the machine comprises a stationary frame designated by a general reference character 20, a row of lift holders or magazines 22, 24, 26, 28, 30 and 32; independent movable lift carriers 34, 36, 115 38, 40, 42, 44, 46 and 48, upon which the lifts are progressively superposed in a plurality of assembling stations, a plurality of endless guiding and supporting tracks 50, 52, 54 and 56 for the movable carriers; 120 an intermittent feed mechanism designated by a general reference character 60 for actuating the movable carriers step-by-step through the assembling stations (Figs. 10 and 15); an endless continuously operated 125 conveyor 64 for rapidly moving the carriers around a portion of the tracks; a pasting apparatus designated by a general reference character 66 for applying paste to certain parts of the machine (Figs. 2, 10 and 19); 130

5 a paste reservoir 68 for supplying paste to the pasting apparatus (Figs. 1 and 2); and a plurality of pivotally mounted swinging picker members 70, 72, 74, 76, 78 and 80, which receive paste from said pasting apparatus and which pick up the lifts from said lift holders and transfer them to said carriers in the successive assembling stations.

10 The stationary frame 20 comprises side pedestal frames, each of which is composed of lower frame members 84, intermediate frame members 86, and upper frame members 88, the respective side pedestals being 15 spaced apart and rigidly connected by means of a horizontal plate 90 for supporting the magazines or wedge holders, and a cross beam 92 upon which the picker members 70, 72, 74, 76, 78 and 80 are pivotally mounted. A plurality of supporting members 94 and 96 project upwardly from the magazine supporting plate 90 to carry the paste reservoir 68, and a plurality of supporting arms 98 and 100 are provided at 25 the respective ends of the machine for carrying the tracks 50, 52, 54 and 56.

The lower pedestal frames 84 (Figs. 1 and 3), are adapted to support a power shaft 102 in suitable bearings, and said shaft carries a fast pulley 104 and a loose pulley 106 for cooperating with a driving belt 108 which is adapted to supply power to the machine when desired. Normally the belt 108 runs upon the loose pulley 106 but 35 may be shifted to the fast pulley 104 at the will of the operator by means of a shifter arm 110 that may be slid longitudinally upon a shaft 112 by means of a rocker arm 114 that is connected to the shifter arm 110 40 by a link 111. The rocker arm 114 is fixed to one end of a rock shaft 116, the other end of which is attached to an operating lever 118 (Figs. 1 and 2). The power shaft 102 is provided with a pinion 120 that meshes 45 with a gear wheel 122 which is carried by a rotatable cam shaft 124 supported in suitable bearings in the lower side frame pedestals 84. The cam shaft 124 is provided with a plurality of cams 126, 127, 128, 130, 50 132, 134 and 136, which are designed and angularly disposed with relation to one another in such manner as to effect the desired time-cooperation of the various mechanisms of the machine, as will be herein- 55 after more fully pointed out.

Since the several picker members operate to intermittently transfer lifts from a suitable supply to assembling stations through which the independent carriers upon which 60 the lifts are progressively assembled are actuated in a series of successive steps, the lifts are conveniently initially held in the magazines or lift holders 22, 24, 26, 28, 30 and 32. The lift holders or magazines 22, 65 26, 28, 30 and 32 are positioned upon the

supporting plate 90 at the back of the machine and are of like construction, being particularly adapted to hold stacks of ordinary even heel lifts of graded sizes. Each lift holder comprises relatively adjustable 70 walls 140 and 148 (Figs. 2, 10 and 18) between which the lifts are stacked. The stationary wall 140 is provided with an upwardly projecting V-shaped portion that has extended face plates 142 secured thereto for 75 engagement with the backs of the stacked lifts. The lower portion 144 of the wall 140 rests upon the supporting plate 90 and is provided with slots 146 through which bolts 147 project for securing the wall in 80 position.

The picker members function to remove lifts from the tops of the stacks within the magazines, and since means is provided to progressively raise the stacks therein to 85 bring the uppermost lifts into suitable positions to be acted upon by the picker members, it is necessary to make provisions for periodically restraining the stacks against the upward actuation of the raising mechanism. For this purpose the wall member 148 of each magazine comprises an upwardly extending member 150 (Figs. 3 and 10) that engages the breast portions of the lifts and is provided with lugs 152 and 154 and with 90 laterally projecting arms 156 and 158. Pivoted between the lugs 154 is a movable clamping member 160 having spaced arms 161 that are disposed above the member 150 and in alignment therewith for engaging 100 the breast portions of the upper lifts in the holder and for definitely positioning the same. The upper inner edges of the arms 161 are beveled to permit the withdrawal of the uppermost lift. The clamp member 160 105 is provided with an integral extension or arm 162, the lower end of which carries a pin 164 which cooperatively engages a slotted end member 166 of a bell crank 167 that is pivoted between the lugs 152 on a pin 168. The short arm 170 of the bell crank has a pivotal connection to the upper end of a rod 172 that extends through openings in the arms 156 and 158 and is slidable therein. A spring 174 surrounds the rod 172 and its upper end engages the arm 156 while its lower end is restrained by means of a collar 176 that is rigidly secured to the rod 172. The spring 174, therefore, tends to force the rod 172 to its lowermost position and thus maintains the upper clamp arms 161 in clamping relation to the upper portion of the stack of lifts contained in the holder.

The wall or member 150 is provided with 125 an integral base portion 178 (Figs. 2 and 3) by means of which it is bolted rigidly to the plate 90 in a suitable manner. By reason of the adjustability of the V-shaped wall 140, it is apparent that the several lift 130

holders may be set or adjusted for any desired sizes of lifts.

The second magazine or lift holder 24 differs from the others, and is particularly adapted to contain wedge-lifts that are alternately or reversely stacked one above the other. Referring particularly to Figs. 4, 5, 6 and 9, the wedge lift holder 24 comprises a rotatable table 182 which is pivotally mounted by means of an extended hub 184 in an opening in the supporting plate 90. Adjustably positioned upon the table 182, are a plurality of wall members 186, 188, 190 and 192, which are disposed opposite each other in pairs to form a substantially rectangular lift receiving magazine.

Each of the wall members 186 and 190 comprises a slotted base member 194 by means of which it is adjustably secured to the table 182 and an upright member 196 that projects to the full height of the magazine. The other pair of wall members 188 and 192 are similar in construction and in operation to the movable wall member of the other magazines or lift holders which have been hereinbefore described, except that the movable clamping members comprise single central arms 163 instead of two spaced arms 161, said arms 163 being bevelled at their upper inner edges to permit the removal of the topmost lift.

Obviously, by suitably positioning the several wall members 186, 188, 190 and 192 just referred to, the magazine or lift holder 24 may be adjusted for any desired size of wedge lifts. In Figs. 4, 5 and 6, the parts are shown as adjusted for a relatively small sized heel lift, while Fig. 7 illustrates the position of the clamps when set for a heel lift of larger dimensions. In the machine illustrated in the drawings, the wall members for the wedge lift holder occupy the positions shown in Fig. 7 and are adapted for relatively large sized lifts.

In order to accentuate the operative positions or to lock the wedge-lift magazine in its positions of rest, the rotatable table 182 is provided with diametrically opposite peripheral notches 198 (Fig. 7) which are adapted to receive a spring pressed detent 200 that is slidably positioned within a guide member 202 that is secured to the plate 90.

The rotatable wedge-lift magazine 24 is given periodic unidirectional half rotations in order to cause the alternately disposed wedge lifts contained therein to be successively, suitably positioned with respect to the swinging pickers to insure their proper transferal and disposition upon the carriers, as will be hereinafter set forth. For this purpose, the table 182 and its hub extension 184 are provided with a central opening to receive a rod 204 (Fig. 6) which projects therethrough and is longitudinally movable with respect thereto. The upper end of the

rod 204 is provided with a plate or follower member 206 upon which the lifts are adapted to rest. The lower portion of the hub extension 184 is slightly reduced in section (Fig. 12) and constitutes a sleeve upon which is loosely mounted a gear wheel 208, while a member 210 having an upwardly projection angular flange 212 is fixed thereto by means of a pin or key 214. Disposed diametrically opposite each other on the inner periphery of the annular flange 212 are pins 216 and 218 (Fig. 11) which are adapted to cooperatively engage the free end of a pawl 220 that is pivotally mounted upon a pin 222 which is carried by the gear wheel 208. The gear wheel 208 has a laterally extending hub portion 224 having an opening 226 therein for the reception of a coiled spring 228 that presses upon the pawl 220 and tends to maintain it in working engagement with one or the other of the pins 216 and 218.

The gear wheel 208 meshes with a toothed segment 230 (Figs. 9 and 11) that is pivotally mounted upon a pin 232 at the end of an arm 234 which constitutes a part of the supporting plate 90. Integral with the segment 230 and on the opposite side of the pivotal stud 232, is an arm 236 carrying a roller 238 that engages and cooperates with the barrel cam 126 (Fig. 2), the latter being secured to the main cam shaft 124, as already explained.

The configuration of the barrel cam 126 is such that the toothed segment 230 is periodically rotated through a limited angle whereby the gear wheel 208 is correspondingly actuated. As the gear wheel 208 is thus rotated in a counter clockwise direction (Fig. 11) the pawl 220, that is carried thereby, is brought into engagement with one of the pins 216 and 218 and is maintained in engagement therewith by the spring 228. Thus, the rotative movement of the gear wheel 208 is communicated to the annular flanged member 212, the latter being fixed to the hub extension 184 of the rotatable table 182. The parts of the mechanism just described are so constructed and operated that each working movement of the toothed segment 230 effects a unidirectional rotative actuation of the table 182 through substantially 180 degrees.

In order to support the stacked lifts and to intermittently raise them in the magazines, the magazines 22, 26, 28, 30 and 32, as well as the rotatable wedge-lift holder 24 are severally provided with follower rods 204 and followers 206 upon which the stacked lifts rest. The several follower rods 204 are positioned and guided through the agency of a plurality of guide rods 239 (Figs. 1 and 2) that are disposed in a row and parallel to the follower rods 204 and are fixed between the supporting plate 90 and an

angle member 240 that is bolted to the lower pedestal frames 84. Angular spacing members 242, having centrally disposed sleeves 244 that are secured to the lower ends of the 5 follower rods 204, are provided with recessed ends 246 which cooperate with and partially and loosely surround the guide rods 239 in pairs (Fig. 9), so as to permit relative vertical movements with respect thereto. In order to exert a constant upward force upon the followers 206 and follower rods 204, flexible cords 248, or the like, are attached to the sleeve members 244 and pass over a plurality of pulleys 250 and 252 10 which are suitably carried by brackets 253 that are secured to the supporting plate 90. The other end of the cords 248 are attached to weights 254. The action of gravity upon these weights, therefore, tends to raise the 15 followers 206 and the lifts that are stacked thereon whenever the clamps of the holders are temporarily released, after the picker members are moved into position above the several magazines, as hereinafter described.

20 In order to effect the release of the movable clamp members of the several magazines or lift holders, a rock shaft 256 is pivotally mounted in the frame of the machine and is disposed parallel to and in back of the row 25 of lift holders (Figs. 1 and 2). This rock shaft 256 is provided with a plurality of fingers 258 (Figs. 2 and 10) that are so positioned thereon as to be capable of being brought into engagement with the lower 30 ends of the several release rods 172 associated with movable clamp members 160 of the lift holders 22, 26, 28, 30 and 32. The oppositely disposed corresponding movable clamp members of the rotatable wedge-lift 35 holder 24 are released by means of arms or fingers 260 and 262 that are also fixed to the rock shaft 256 and directly beneath the release rods 172 of the wedge-lift holder.

40 The rock shaft 256 is periodically actuated by means of the cam 130 through the agency of an arm 264 (Figs. 1, 2 and 3) that is secured to substantially the middle thereof. This arm 264 has a pivotal connection to one end of a rod 266, the other end of which 45 is pivotally connected to an end of an arm 268 constituting a part of a bell crank that is pivotally mounted upon a rock shaft 270 and having another arm cooperating with the cam 130 (Fig. 2). The cam 130 is so constructed as to produce periodic movements 50 of the rock shaft 256 whereby the several tripping arms 258, 260 and 262 are caused to engage the lower ends of the release rods 172 of the respective lift holders, whereby 55 the clamps are temporarily released when the picker members are in position above the several magazines. The several followers 206, by the aid of the weights 254, are therefore permitted to raise the lifts in the several 60 magazines or holders against the picker 65

members which serve as stops, whereby the uppermost lifts are freely disposed between the beveled edges of the clamps and may be subsequently removed by the picker members, as will be fully set forth.

70

The construction and operation of the several movable carriers upon which the lifts are assembled will now be set forth. All of the carriers 34, 36, 38, 40, 42, 44, 46 and 48 are of like construction and each comprises (Fig. 16) a main substantially horizontal supporting plate 276, the opposite sides of the front end thereof being provided with rollers 278 and 280 which are respectively adapted to travel within the tracks 75 50 and 56. Projecting downwardly from substantially the middle of the rear end of the supporting plate 276 is a lug 282 that is provided with a roller 284 which is adapted to travel within the track 54. The tracks, 80 50, 56 and 54, therefore, serve to guide and to support each of the movable carriers, as will be explained. The supporting plate 276 of each carrier is further provided at one side of the rear end thereof with a depending lug 286 for engagement with a pusher member 288 that is carried by the conveyor chain 64 in a manner to be hereinafter set forth. Moreover, the forward end of each of the carrier plates 276 is provided with a 85 downwardly projecting lug 290 for engagement with a portion of the carrier feed mechanism 60 to be described.

The guiding and supporting tracks 50, 54 and 56 and the track 52 are in the general 100 form of elongated ellipses and comprise semi-circular grooved end members or plates 294 and 296 and suitable grooved intermediate straight sections that are substantially horizontal, the component straight sections 105 of each track being disposed in a vertical plane, one above the other (Figs. 3, 10 and 15). The end members 296 of the several tracks at one end of the machine are supported upon a shaft 298 (Fig. 15) which is carried by bearings 300 forming parts of the supporting arms 98 which have previously been referred to as secured to one of the intermediate side pedestal members 86. The end members 294 (Fig. 3) of the several 110 115 tracks at the other end of the machine are of similar form and are carried upon a shaft 302 which is mounted in the upper end of the supporting arms 100 that are secured to the intermediate side pedestal 86 at the other 120 end of the machine.

The tracks 50 and 56 are spaced apart horizontally a distance sufficient to enable their grooves to accommodate the rollers 278 and 280 at the front end of each carrier, 125 while the track 54 is disposed substantially midway between the tracks 50 and 56 and within them. The groove of the track 54 is adapted to receive the roller 284 of each carrier, as hereinbefore set forth. The track 130

52 comprises an integral part of the track 50, the two tracks being joined by a narrow connecting portion 53, as shown in Figs. 13 and 16. The end members 294 and 296 of 5 the several tracks are semi-circular in form and are provided with grooves that correspond to and register with the grooves of the straight portions of the tracks 50, 52, 54, 56, as will be understood. The straight portions 10 of all the tracks are entirely removable, being secured to the semi-circular end track portions by means of suitable plates 304 and screws 306.

The several movable carriers 34, 36, 38, 40, 15 42, 44, 46 and 48 are adapted to be intermittently actuated along the upper straight portions of the guiding and supporting tracks that are disposed at a slight downward inclination toward the last assembling 20 station. It is desirable to provide means whereby the inclination of the upper straight portions of the tracks may be adjusted to suit varying characteristics of the stock or a change in the style of heel being built. 25 Obviously the necessary degree of inclination of the tracks depends upon the height of the heel to be built. The height of the heel may be varied by increasing the number of lifts, or by a change in the thickness of the stock 30 of which the lifts are composed. Such means is shown particularly in Fig. 3, to which reference may be had, and which illustrates the arms 100 that support the shaft 302 as secured to the intermediate side pedestal 35 frame 86 by means of bolts 308 that project through slots 309 in the base portions of the arms and into said pedestals. Between the arms 100, the shaft 302 is provided with a vertically disposed link 310 which has a 40 pivotal connection to a bifurcated member 312 that is horizontally disposed and pivoted upon a pin through lugs 314 that form integral parts of a plate member 316 which may be suitably bolted to the side pedestal 45 frame 86. The member 312 is provided with an integral downwardly projecting arm 318 having an adjusting bolt 320 associated therewith. The end of the bolt 320 is adapted to bear upon a boss 322 forming a part 50 of the plate member 316. In order to adjust the upper straight portions of the tracks to any desired inclination, it is only necessary to loosen the bolts 308 through the slotted arms 100 and to subsequently turn the adjusting bolt 320 in the proper direction to either raise or lower the arms 100, after 55 which said arms may be rigidly clamped in their adjusted position.

It has already been pointed out that this 60 invention is particularly adapted for building wedge heels in which one or more wedge lifts are employed, and, furthermore, that the machine is so constructed and operated as to produce wedge heels in which the 65 breast edges of the component lifts are in

alignment to ensure a substantially plane breast surface. One feature of the machine that contributes to this end is the means by which each carrier is tilted or inclined just prior to reaching its wedge-lift assembling 70 station or receiving position. Referring particularly to Fig. 14, two carriers are illustrated, one in the first assembling station with one even lift disposed thereon, and the other in its wedge-lift assembling station 75 in which a wedge-lift has been superposed upon the even lift. Intermediate these two assembling stations, the middle lower track 54 is provided with a drop or incline 326 which permits the roller 284, and therefore 80 the rear end of the carrier, to be dropped with respect to its original position, thereby effecting a rearward tilting or inclination of the supporting plate of the carrier. By properly choosing the degree of drop of the 85 middle track 54, any desired inclination of the carrier may be attained, and this inclination should be such as to cause the upper surface of the wedge-lift, after being assembled, to be substantially horizontal, in order 90 to facilitate the further assembly of additional lifts, and also to conduce to the building of a wedge heel having a substantially plane breast surface.

The machine, as illustrated in the drawings, is adapted to apply a single wedge-lift, but it will be readily understood that any desired number of wedge-lifts may be employed, which, of course, necessitates a corresponding number of drops similar to the 100 drop 326 in the middle track 54. Since the straight sections of the tracks are removable, as hereinbefore pointed out, it is only necessary to insert a middle track section having the desired number of drops to accommodate any number of wedge-lifts. Obviously, if more than a single wedge lift is employed, a corresponding number of rotatable wedge-lift holders or magazines will be required. 110

Referring to Figs. 2 and 3, it will be noted that there are two more carriers than there are lift assembling stations which correspond to the number of picker members embodied in the machine. The carrier 34 occupies an "initial" or "preliminary" position, from which it is actuated into the first lift-receiving or assembling station. The carrier 48 occupies a "finished" position beyond the last lift-assembling station 120 in which the heel is completed and is ready to be discharged into a suitable receptacle 327 (Fig. 1). The other carriers 36, 38, 40, 42, 44 and 46 are illustrated in the successive lift-assembling stations, in which the heels are progressively built up, one lift at a time, until the desired number of lifts have been superposed and the heel completed. All of the carriers, as hereinbefore stated, 125 are actuated intermittently and step-by-step 130

through the several assembling stations, and the mechanism for effecting this actuation will now be described.

Particular reference may be had to Figs. 5 10 and 15, in which is illustrated a longitudinally reciprocable rod 330 which is slidably positioned in suitable bearings 332 associated with the upper straight section of the track 54, and which is provided with a 10 toothed segment 336. The rod 330 is also provided with a fixed spool 338, between the flanges 340 of which are positioned rollers 342 that are mounted upon pins 344 carried in a bifurcated yoke member 346 that is 15 provided at the upper end of a bell crank or shipper member 348. This bell crank or shipper member 348 is provided with a hub 350 that is rotatably mounted upon a shaft or stud 352 which is carried in bearings 354 20 that constitute parts of an arm 356 (Figs. 1 and 3) that is rigidly fastened to an intermediate side pedestal frame 86. The bell crank 348 comprises an extended arm 358 which has a universal connection 360 to the 25 upper end of a link 362, the lower end of which has a universal connection 364 to the end of an arm 366 that constitutes a part of a bell crank. The bell crank just referred to is pivotally mounted upon the crank shaft 30 270, and its other arm 368 is provided at its outer end with a roller 370 that cooperates with a suitable cam path in the cam 132 that is fixed to the cam shaft 124. By means of the operative connections just described, it 35 is evident that by suitably designing and positioning the cam 132, the rod 330 is reciprocated periodically through a definite length of travel and in the proper time-cooperation to other elements of the ma- 40 chine.

The rod 330 is provided with a plurality of adjustably positioned and spaced fingers 372 which project upwardly therefrom. Each of the fingers 372 forms an integral 45 part of a split hub member 374 that is provided with slightly spaced lugs 376 through which a screw 378 projects for the purpose of rigidly securing the hub portion to the rod 330. There are as many fingers 372 as 50 there are movable carriers, and these fingers are so disposed as to be brought into cooperative engagement with the middle downwardly projecting lugs 282 of all the carriers. In Fig. 15, the parts are illustrated in 55 the positions which they occupy after having completed a forward actuation of all of the carriers. Initially the shipper member 348, the rod 330 and its associated fingers 372 occupy positions to the left of those illustrated 60 in Fig. 15.

The toothed segment 336 which has been described as fixed to the rod 330 is adapted to mesh with a cooperating toothed seg- 65 mental sleeve 380 of materially greater

length than the segment 336, and which is fixed to a rod 382 that is disposed parallel to but slightly above and to one side of the rod 330 (Fig. 10) and is mounted in bearings 381 (Fig. 2) that are associated with the middle track 54. The toothed segmental 70 sleeve 380 is provided with an integral arm 384 that has a pivotal connection to the upper end of a rod 386 (Fig. 1), the lower end of which is pivotally secured to an arm 388 of a bell crank, the latter being rotatably 75 mounted upon the crank shaft 270 and having an arm 390 that is provided with a roller 392 which cooperates with the cam 128 upon the cam shaft 124.

The rod 382 (Fig. 15) extends throughout 80 substantially the length of the machine and is provided with a plurality of spaced slide- 85 able sleeves 396, each having oppositely disposed slots 398 in one end and being provided with a laterally extending finger 400 which is adapted to engage the downwardly 90 projecting lugs 290 of the carriers. The sleeves 396 are loosely splined to the rod 382. The rod 382 is also provided with collars 402 which are pinned thereto and each 95 of which is provided with longitudinally extending tongues 404 which are disposed on opposite sides of the rod and are adapted to project into the slots 398 of the next adjacent slotted sleeve member 396. Coil 100 springs 406 surround the rod between the fixed collars 402 and the slideable sleeves 396 of which the finger 400 is an integral part. The several sleeves 396, therefore, are constantly acted upon by the springs 406 which 105 tend to maintain them in their left-hand positions, as viewed in Fig. 15. By reason of the splined connections between the sleeves 396 and the rod 382, it is clear that any ro- 110 tative movement which is given to the 105 toothed segmental sleeve 380 by the cam 128 through the intermediate connections hereinbefore described, is imparted to the rod 382 and, therefore, to the fingers 400 that are associated therewith. Obviously, ro- 115 tative movements of the rod 382 are transmitted to the reciprocating rod 330 through the agency of the toothed segmental sleeve 380 and the cooperating toothed segment 336.

Initially, the rod 330 and its fingers 372 and the rod 382 with its fingers 400 occupy 115 their extreme left-hand positions, as viewed in Fig. 15, and also the relative angular positions illustrated in Fig. 19. The cams 128 and 132 are angularly positioned with 120 respect to one another so that a rotative movement is first imparted to the respective rods 382 and 330, whereby the several fingers 400 and 372 are rotated toward each other into vertical positions, the fingers 372 being 125 brought into engagement with the lugs 282 of the several carriers, and the fingers 400 being brought into the path of travel of the several lugs 290 that are associated with the 130 respective carriers. Having actuated the

5 fingers 372 and 400 into the positions just indicated, the cam 132 causes the shipper lever 348 to actuate the rod 330 to the right, as illustrated in Fig. 15, while maintaining 10 the vertical positions of the respective fingers 372 and 400. This longitudinal movement of the rod 330 is permitted inasmuch as the toothed segment 336 is free to move longitudinally while being maintained in cooperative 15 engagement with the toothed segmental sleeve 380, as will be understood.

It has already been pointed out that one 20 of the essential features of the machine is to build wedge heels having substantially plane breast surfaces in order to obviate the necessity of a preliminary breast trimming operation before compressing the heel piles into heel blanks. The desired alignment of the breast edges of the component lifts is effected in two ways, which mutually contribute 25 to the desired end. The tilting or inclining of the several carriers, in a position just ahead of their wedge-lift assembling stations, performs one of the necessary functions, while the other is secured by adjusting or setting the several actuating fingers 372 upon the reciprocable rod 330 in order to cause the carriers to be actuated through different predetermined distances, it being 30 understood that the picker arms always occupy precisely the same invariable positions in the several assembling stations at the time when the lifts are deposited upon the carriers.

35 If a single wedge lift is to be employed, as in the machine illustrated, it is necessary that each carrier should be actuated a slightly greater distance from its initial or preliminary position to its first assembling station than it is actuated between any subsequent assembling stations, that is to say, the advancement of each carrier to its wedge-lift assembling station and to its subsequent assembling stations should be slightly 40 less than the distance of travel into its first assembling station. Moreover, if a single wedge-lift is employed, the distance of travel into the wedge-lift assembling station and all subsequent stations should be equal.

45 The reason for these requisite relative distances of travel of the several carriers may be better understood from an examination of Fig. 8, which illustrates a completed heel in position upon its carrier. It will be remembered that in the first assembling station the carrier is maintained in a substantially horizontal position to receive the first even lift. Between the first and second assembling stations, the second being the one 50 in which the wedge-lift is superposed, the drop in the middle lower track effects a tilting or inclination of the carrier sufficient to accommodate the taper of the wedge-lift and maintain its upper surface in a substantially horizontal position. This tilting of the car-

rier, of course, tilts the first lift, and therefore its breast surface is slightly inclined to its initial vertical plane shown by the dotted line. If the travel of the carrier into its wedge-lift assembling station and subsequent stations were equal to the travel thereof into the first assembling station, it is evident that the wedge-lift and all subsequent lifts would be offset or overhung with respect to the lowermost lift. Thus, 75 it would be necessary either to trim off the overhanging portions of the breasts of all of the subsequent lifts, or to subject this relatively large projecting or offset portion to an excessive pressure in the heel compressing operation in order to form a smooth 80 plane breast surface for the heel.

However, by adjusting the positions of the several fingers 372 upon the rod 330 the length of travel of the carriers into the 85 wedge-lift assembling station and all subsequent stations is made a sufficiently shorter distance to cause the wedge-lift and subsequent lifts to have their breast surfaces aligned directly over the uppermost breast 90 edge of the lower tilted lift. In this manner, a substantially plane breast surface for the completed heel is ensured, the only deviation therefrom being the slight angular projection of the breast portion of the lowermost lift, as clearly shown in Fig. 8.

With a comprehension of the reasons for adjusting the fingers 372 along the rod 330 so as to give a shorter travel of the carriers into the wedge-lift assembling station and 100 all subsequent stations, it will be understood that upon the initial forward actuation to the right of the rod 330, the left-hand finger 372 (Fig. 15) is at once brought into engagement with the lug 282 of the empty 105 carrier in its preliminary or initial position, and therefore the actuation of this carrier is immediately effected. Just subsequent to the initial movement of the first carrier and after a slight distance has been 110 traversed, the other fingers 372 are brought into engagement with the lugs 382 of the remaining carriers, whereby their actuation is initiated. When the several carriers are materially advanced, the lugs 290 associated with the forward ends thereof are 115 brought into engagement with the spring-pressed fingers 400 which serve to grip the carriers. As the actuation is continued the springs 406 yield accordingly, while maintaining the several carriers gripped in position throughout the remainder of the movement. When the actuation of the carriers is completed, as shown in Fig. 15, the springs 406, still being held under compression, act 120 upon the fingers 400, and therefore the carriers are prevented from overshooting their positions and are definitely and positively brought to rest in their proper stations after having travelled predetermined distances 125 130

as prescribed by the relative adjustments of the fingers 372.

Subsequent to the advancement of the carriers, the cam 128 effects an opposite rotation of the rod 382 whereby the fingers 400 which are still spring-pressed are rotated to the left, as shown in Fig. 10, to disengage the several lugs 290. As soon as this disengagement is effected, the several springs 10 406 act upon the fingers 400 to return them to the left to their initial positions, this movement being permitted by the tongue-and-groove lost-motion connections between the slidable sleeves 396 and the fixed collars 15 402.

Immediately subsequent to this disengagement, the fingers 372 are rotated downwardly, in a clockwise direction as shown in Fig. 10, to disengage the lugs 282 at the rear 20 end of the several carriers. The cam 132, through its operative connections, causes the slipper lever 348 to actuate the rod 330 to the left (Fig. 15) to its initial position. The several parts of the intermittent carrier-feed mechanism are then in position to repeat the cycle of operation described to again 25 advance the several carriers occupying the initial and assembling stations through predetermined distances into their next succeeding assembling stations, as will be understood. At each step in the feed of the carriers, a heel is completed in the last assembling station and is advanced upon its carrier into the "finished" station.

Having determined the means and manner of actuating the several movable carriers from their "initial" or "preliminary" position through the successive assembling stations to the "finished" position, the actuation 25 of the carriers from the "finished" position around the remaining portion of the track and back to the "initial" position will be set forth. The return movement of the carriers from the "finished" position to the "initial" position is primarily effected by means of the continuously operating endless chain conveyor 64 (Figs. 2 and 13) which is carried upon sprockets 410 and 412 that are respectively mounted upon the shafts 298 and 302 (Figs. 2 and 3), upon which the several tracks are supported. The shaft 298 is rotatably mounted in bearings 300 (Fig. 1) which constitute parts of the supporting arms 98 that are bolted to one of the intermediate side pedestal frames 86 and one end thereof is provided with a skew gear 414 (Fig. 18) that meshes with a cooperating gear 416 that is carried by a shaft 418. The shaft 418 is suitably supported by the frame 60 and is provided with a sprocket 422 (Fig. 1) which carries a chain 424 that also cooperates with a sprocket 426 which is fastened to the cam shaft 124. In order to obtain the desired tension upon the chain 424, an adjustable idler sprocket 428 is provided which

engages the chain and is supported upon a bracket 430 that is secured to the frame.

By reason of the operative connections just described, the shaft 298 and its sprocket 410 are given a continuous rotative movement whenever power is supplied to the machine, as will be understood. Thus, the chain 64 and the sprocket 412 at the other end thereof are continuously actuated.

Referring to Fig. 10, it will be noted that 75 the chain 64 is disposed intermediate the tracks 52 and 54 and immediately adjacent the track 52. The chain 64 is provided with the pusher member 288 (Fig. 13) of substantially triangular shape, which is pivoted at 80 one of its corners to the chain upon a pin 434. The pusher member 288 is provided at another corner with a roller 436 which is pivotally mounted upon a pin 438 and projects laterally into the groove of the track 85 52, in which it is adapted to travel. By reason thereof, the pusher member 288 is normally maintained in engagement with the lug 286 of one of the carriers, as shown in Fig. 16 and in dot and dash lines on the 90 curved portion of the track in Fig. 13, whereby the carrier is actuated. Just ahead of the "initial" or "preliminary" position of the carriers, which is occupied by carrier 34 in Fig. 13, a break 440 in the lower flange 95 442 of the track 52 is provided, in order to permit a downward movement of the leaf member 288 and its roller 436 when said pusher member engages a stationary stop roll 444, which is positioned just above the 100 break in the track and upon the portion 53 which joins the tracks 50 and 52, for the purpose of effecting the disengagement of the pusher member 288 and the carrier upon which it acts. To accommodate the roller 105 436 of the pusher member 288 in its depressed position and to maintain it in such position throughout the travel of the chain conveyor and the pusher member through the "preliminary" position and the several 110 assembling stations, an auxiliary grooved track 446 is provided, this track being conveniently formed integral with the track 52 and disposed directly beneath it.

Between the last assembling station, occupied by carrier 46, and the "finished" 115 position, occupied by carrier 48, the lower flange 448 of the auxiliary track 446 is inclined upwardly to constitute a cam for engaging the roller 436 of the pusher member 288, and thus forcing said member upwardly 120 into its normal operative position, whereby it is brought into engagement with the carrier 48 which occupies the "finished" position. The pusher member 288 and roller 125 436 are shown in dot and dash lines in Fig. 13 on the point of being brought into engagement with the inclined cam surface 448. When the roller 436 has travelled up said cam surface and through a break 449 in the 130

flange 442 of the track 52, it is again brought into travelling engagement with the track 52, where it is maintained throughout the remaining portion of its travel. Obviously, 5 when the pusher member 288 is raised into its operative position by means of the cam surface 448, it is brought into engagement with the lug 286 of the carrier 48 which occupies the "finished" position, and thus 10 actuates said carrier around the track until it reaches the "initial" position. The stationary stop roll 444 then again engages the pusher member 288 to depress it and its roller 436 into the auxiliary track 446, in 15 which it travels until it is again brought into operative engagement with the carrier which then occupies the "finished" position. By reason of the construction set forth, it is evident that the continuously operated 20 chain conveyor 64 is disengaged from the carriers just ahead of their "preliminary" position and remains disengaged throughout the several assembling stations until the engagement is again effected with the carrier 25 in the "finished" position, after which that carrier is returned to the "preliminary" position. This return movement of the carriers is preferably effected with dispatch in order to increase the capacity of the machine 30 for work, without the use of extra idle carriers. During this period of disengagement of the chain 64 with the carriers, said carriers are intermittently actuated step-by-step through the several assembling stations 35 in the manner hereinbefore set forth, during which period the lifts are successively superposed to form heels.

The pasting apparatus 66 comprises (Figs. 2, 3, 10, 17 and 19) an elongated trough 450 40 in which a rotatable paste roller 452 and a perforated supply pipe 454 are disposed in side-by-side relation. The trough 450 is provided with extended end portions 453 that removably rest in openings 455 in upwardly 45 projecting end members 457 that are integrally associated with the base plate 456. A bottom groove is provided throughout the length of the base plate 456 to receive a bar 458 which extends the entire length thereof. 50 The bar 458 is supported at one end by a plate 460 that is bolted to the left-hand pedestal frame 86 (Figs. 3 and 19) and at the other end by a bracket 461 (Fig. 2) that constitutes a part of the arm 98. The paste 55 roller 452 is rotatably mounted within the trough 450 upon the end members 457, and its extended shaft 462 (Figs. 2 and 10) is provided with a gear 464 which is adapted to mesh with a pinion 466 that is carried on 60 a shaft 468 that is located directly below the paste roller shaft 462 and which is rotatably mounted in the bracket 460. A skew gear 470 (Fig. 18) is fixed to the shaft 468 and engages a cooperating gear 472 that is 65 secured to the end of the shaft 298, upon

which the sprocket 410 is mounted. Inasmuch as the shaft 298 is continuously rotated whenever power is applied to the machine, it is evident that the paste roller 452 is similarly actuated through the gear train just 70 described.

The perforated pipe 454 is removably set in recesses 473 (Fig. 17) in the extended end portions 453 of the trough 450, and has one of its ends connected to the bottom of the 75 paste reservoir 68 by means of a suitable flexible pipe 474, which is provided with a valve 476 and a detachable coupling 478 (Figs. 2 and 19). Paste is thus supplied by gravity from the reservoir 68 through the 80 flexible pipe 474 to the perforated pipe 454, from whence it is discharged through the perforations into the trough 450.

In the operation of machines of this character which employ paste, it becomes necessary to clean the pasting apparatus frequently, and, therefore, the paste roller 452 and perforated pipe 454 contained therein are adapted to be readily removed for this purpose by disconnecting the coupling 478 90 and lifting out the trough 450.

Referring now to Figs. 1, 2, 3, 17, 18 and 19, the swinging picker members 70, 72, 74, 76, 78 and 80, which correspond in number to the lift-holders or magazines 22, 24, 26, 28, 30 and 32, are pivotally mounted in spaced relation above the cross-beam 92 which rests upon the upper ends of the intermediate side pedestal frames 86, and which is provided with bosses 480 having 100 openings therein through which pivotal bolts 482 severally project.

The several swinging picker members 70, 72, 74, 76, 78 and 80 are of like construction, and each comprises (Figs. 17 and 19) a 105 horizontal arm 484 having laterally projecting longitudinal ribs 486 on the respective sides thereof and a plurality of upwardly projecting spaced lugs 488 that are disposed substantially midway between its 110 ends. Each picker arm 484 is pivotally mounted at one end upon the cross-beam 92, as just set forth, and the other end or head 489 thereof is bifurcated to provide a pair of vertically spaced lugs 490. A rod 492 is 115 slidably mounted in an opening through the head 489. The upper end of the rod 492 is provided with fixed spaced collars 494 and the lower end thereof carries a lift-engaging plate 496 of substantially the contour of a heel lift. The lift-engaging plate 496, associated with the picker member 72 that handles the wedge lifts, has a pivotal connection 497 (Fig. 10) with the rod 492 so that it may readily accommodate itself to 120 the inclination of the uppermost lift in the magazine. The other plates 496 are fixed to the respective rods 492. An auxiliary plate 498 loosely surrounds the lower portion of the rod 492 and is provided with 125 130

a plurality of lift-stripping pins 500 which are adapted to be projected through openings 502 in the lift-engaging plate 496, in a manner to be hereinafter set forth. The auxiliary plate 498 and its associated pins 500 are normally maintained in their raised position by means of a coil spring 504 which surrounds the rod 492 and is disposed between the auxiliary plate 498 and the lift-engaging plate 496. It will be observed that the spring 504 normally maintains the picker plate 496 in a horizontal position from which it may tilt in either direction on the pivot 497 as it meets a lift whose face is inclined to the horizontal. The auxiliary plate 498 is secured to the lower end of a guide and actuating rod 506 which projects upwardly through openings in the picker arm lugs 490.

20 Each of the picker arms 484 is provided with an arm 508 (Fig. 2) which is integral therewith and projects beyond the pivot on which the picker arm is mounted. The ends of the several arms 508 are connected by means of a bar 510 that is pivotally associated therewith, whereby the several picker members are mechanically interconnected in such manner as to render them concurrently operative, while maintaining them in parallelism.

25 The right-hand picker member 80 (Figs. 2 and 17) is also provided with an arm 512, by which the several picker members are actuated. The arm 512 has a universal connection 514 with one end of a rod 516, the other end of which has a similar universal connection 518 (Figs. 1 and 2) with the end of an arm 520 which constitutes a part of a bell-crank that is pivotally mounted 30 upon a shaft 522. The other arm 524 of the bell-crank just referred to, has a pivotal connection to one end of a rod 526, which has its other end pivotally connected to an arm 528 of a bell-crank that is rotatably mounted upon the crank-shaft 270. This bell-crank also comprises an arm 530 that carries a roller 532 which travels in a suitable cam path on the cam 134 that is fixed to the cam shaft 124. The cam 134 is de- 35 signed and angularly positioned with respect to the other cams on the cam shaft 124, so as to cause the several picker members 70, 72, 74, 76, 78 and 80 to be concurrently swung from definite positions over 40 the respective movable carriers 36, 38, 40, 42, 44 and 46, as illustrated in Fig. 2, to predetermined positions directly over the respective lift-holders or magazines 22, 24, 26, 28, 30 and 32, as illustrated in Fig. 18.

45 During the swinging movement of the picker members toward the lift magazines, the several lift engaging plates 496 engage the continuously rotated paste roller 452, whereby paste is applied to the bottom surfaces of the several lift-engaging plates

496. Figure 17 illustrates the relative positions of the picker members in the intermediate step in their travel toward the lift magazines, in which they engage the paste roller 452 and are thus supplied with paste. 70

When the several picker members and their associated lift-engaging plates 496 occupy positions over the lift magazines, as shown in Fig. 18, the cam 127 permits each of the plates 496 to be depressed into their stop positions slightly above the magazines directly beneath them, by means of coil springs 533 (Figs. 17 and 19) which exert a constant downward force upon operating levers 534 which are pivoted between the upwardly projecting lugs 488 of the picker arms 484. The outer end of each lever 534 is bifurcated to form a yoke 535, the arms of which are provided with rollers 537 that are positioned between the collars 494 which are attached to the rod 492. The other end of the lever 534 is located just beneath and in engagement with a cross-bar 536, the respective ends of which are secured to vertically reciprocable cross-heads 538 which are adapted to travel between guide members 540 that are secured to inner surfaces of the respective upper side pedestal frames 88. The movable cross-heads 538 are supported upon vertical rods 542 (Figs. 1 and 3), the lower ends of which are pivotally connected to arms 544 that are fixed near the respective ends of the crank-shaft 270. The crank-shaft 270 is provided with a suitable fixed arm carrying a roller (not shown) which co-operatively engages a cam path in the cam 127 that is secured to the cam shaft 124. The configuration of the cam 127 is such that, through the connections just described, the cross-bar 536 is vertically reciprocated 100 in proper time-cooperation with the other elements of the machine in such manner as to periodically permit the springs 533 to lower the lift-engaging plates 496 into their stop positions immediately above the magazines, and to subsequently act downwardly upon the respective levers 534 and thus cause the several plates 496 to be raised into the positions shown in dotted lines in Fig. 19.

105 Prior to the raising of the lift-engaging plates 496, in the manner described, the several lift clamping members 160 and 163 (Figs. 10 and 18) of the lift magazines are momentarily released by the engagement of the release arms 258 and 263 with the lower ends of the release rods 172 in accordance with the action of the cam 130. The stacks of lifts within the magazines are therefore permitted to be temporarily fed upwardly, whereby the uppermost lifts are urged into 110 engagement with the lower surfaces of the several lift-engaging plates 496 which have already been coated with paste. The picker members, therefore, serve as temporary stops to prevent the stacks of lifts from be- 115

120 125 130

ing forced out of the upper ends of the magazines, and being loosely positioned between the beveled upper ends of the magazine clamps, the uppermost lifts adhere to the plates and may be picked up or raised thereby during their subsequent elevating movement.

The lift-engaging plates 496 and the lifts which adhere thereto are raised in this manner to a height which is greater than that of the paste roller 452, so that the lifts which are picked up by the lift-engaging plates 496 pass over the paste roller without engagement therewith as the cam 134, through 10 the connections already described, subsequently causes the several picker members to be concurrently swung back to their normal definite positions directly above the several movable carriers which occupy the respective assembling stations, as illustrated in Fig. 2 and in dotted lines in Fig. 19. When this relationship of parts obtains, the cam 127 causes the cross-bar 536 to be raised in order to permit the coil springs 533 to 20 depress the lift engaging plates 496 and the lifts carried thereby until said lifts rest upon the carriers or the assembled lifts that are already superposed thereon, as the case may be. The several lifts which adhere to 25 the lift-engaging plates 496 of the several picker members are thus transferred from the magazines to definitely determined positions on the respective carriers which occupy the assembling stations.

30 It will be understood that since each picker member always transfers its lifts to exactly the same predetermined position with respect to the respective assembling stations, it becomes necessary to suitably adjust 35 the length of travel of the carriers from one station to another, as has already been set forth, in order to insure the production of a wedge heel having the characteristics illustrated in Fig. 8 and hereinbefore described 40 in detail.

45 After having deposited the lifts upon the carriers or the previously assembled lifts, the cam 127, through the agency of the mechanism actuated thereby and already described, effects a temporary slight elevation of the lift-engaging plates 496. During this operation, the transferred lifts are released from the plates 496 in the following manner and by the mechanism to be described. A 50 rockshaft 554 (Figs. 1, 17 and 19) is rotatably mounted at the upper ends of the respective upper side pedestal frames 88 and extends longitudinally of the machine. Pinned thereto in spaced relation are a plurality of collars 556, each of which is provided with a laterally projecting curved arm 558. Adjacent to the several collars 556 and loosely surrounding the rockshaft 554, are a plurality of levers 560, having integral 55 laterally extended arms 562 which severally

cooperate with and engage the corresponding arms 558 of the respective fixed collars 556. The arms 558 and 562 are provided with openings to receive bolts 564, and the openings in the arms 558 are tapered. (Fig. 19) to permit of considerable relative movement between said arms and the bolts 564 which project through them. The upper ends of the bolts referred to are provided with adjustable nuts 566, and coil springs 568 surround the respective bolts and are disposed between said nuts and the arms 558 for the purpose of establishing yielding connections between the rockshaft 554 and the several levers 560, to accommodate different 70 heights of superposed lifts. An arm 570 is fixed to the shaft 554, and its outer end has a pivotal connection to the upper end of a rod 572, the lower end of which is pivotally connected to an arm 574 (Fig. 1) of a bellcrank, 75 having another arm 576 which carries a roller 578 that cooperates with the cam 136 upon the cam shaft 124. The cam 136 is adapted to periodically raise and lower the several levers 560 through the connections 80 just described, and in such time-cooperation with the swinging movements of the picker members as to cause the levers to act upon the upper ends of the rods 506, concurrently 85 with the temporary elevation of the lift-engaging plates. As the several rods 506 are depressed, the auxiliary plates 498 and their associated lift stripping pins 500 are correspondingly depressed, and the pins are 90 forced through the openings 502 in the lift-engaging plates 496 and into engagement with the lifts which adhere thereto and have just been transferred from the magazines. The depression of the pins 500, compresses 95 the springs 504 and, in conjunction with the concurrent temporary elevation of the plates 496, strips the lifts therefrom and maintains them in position upon the carriers or the superposed lifts already assembled thereon.

100 Immediately after separating the lifts from the lift-engaging plates in the manner described, the cam 136 effects the elevation of the actuating ends of the levers 560, and the springs 504 force the auxiliary plates 498 and their associated stripper pins 500 and 105 guide rods 506 upwardly to their normal positions.

110 The cycle of operation of the picker members is thus completed, and after the movable carriers are advanced a step into their 115 respective succeeding assembling stations, the picker members are caused to function again through the same cycle whereby additional lifts are picked up from the lift holders, transferred to the respective carriers, 120 and superposed thereon to progressively build up wedge heels having the desired characteristics.

125 From the foregoing description, it will be understood that a plurality of heels are in 130

the process of building at the same time, single lifts being concurrently superposed upon the carriers in the respective stations at each step of advancement thereof, and one heel being completed in the last assembling station at each transferring movement of the picker members.

Throughout the specification and claims, the terms "lifts" and "heel-lifts" are employed in an inclusive sense as defining any blank or layer of material capable of being handled by instrumentalities of the character described, more particularly, such blanks as are useful in the formation of heel piles from which heels are ultimately produced, irrespective of the particular shape of the blank or the nature of the material of which it is composed.

The nature and scope of the invention having been indicated and the preferred embodiment of the invention having been specifically described, that which is claimed as new, is:—

1. A heel-building machine having, in combination, a plurality of lift holders, corresponding in number to the component lifts in the heels to be built, supporting means upon which the heels are assembled, and a corresponding number of rotatably mounted picker members for concurrently transferring lifts from the respective lift holders and definitely positioning them upon said supporting means.

2. A heel-building machine having, in combination, a plurality of lift holders, a plurality of independently movable carriers upon which the lifts are assembled, means for intermittently moving said carriers, and a plurality of rotatably mounted picker members for concurrently transferring lifts from said lift holders to said carriers.

3. A heel-building machine having, in combination, a plurality of lift holders, a plurality of movable carriers upon which the lifts are assembled, and a plurality of paste picker members for severally taking single lifts from the respective holders and depositing them upon the respective carriers.

4. A heel-building machine having, in combination, a plurality of lift holders, a plurality of independently movable carriers upon which the lifts are assembled, and a plurality of interconnected swinging picker arms adapted for concurrent parallel movements for transferring lifts from the respective lift holders to the respective carriers.

5. A heel-building machine having, in combination, a plurality of lift holders, a plurality of movable carriers upon which the lifts are assembled, a plurality of picker arms pivotally mounted in the same plane and adapted to be moved back and forth between said lift holders and said carriers,

means associated therewith for picking up lifts from the respective holders and depositing them upon the respective carriers, and means for applying paste to said last means.

6. A heel-building machine having, in combination, a plurality of lift holders, supporting means upon which the lifts are assembled, a plurality of concurrently movable picker arms pivotally mounted to move back and forth in the same plane between said lift holders and said supporting means, lift-engaging members severally associated with said arms, means for causing said members to engage the exposed lifts in the respective holders, and means for releasing the lifts therefrom and depositing them upon the supporting means.

7. A heel-building machine having, in combination, a lift holder, a support upon which a heel is assembled, a movable picker member for transferring a lift from said holder to said support, and means for applying paste to a portion of said picker member whereby the lift is caused to adhere thereto.

8. A heel-building machine having, in combination, a lift holder, a support upon which a heel is assembled, a movable picker member for transferring a lift from said holder to said support, and means in the path of travel of a portion of said picker member for applying paste to said portion during its movement to said holder.

9. A heel-building machine having, in combination, a lift holder, a support upon which a heel is assembled, a movable picker member for transferring a lift from said holder to said support, and a paste applying roller disposed intermediate said holder and said support for coating a portion of said picker member with paste.

10. A heel-building machine having, in combination, a lift holder, a support upon which a heel is assembled, and a movable picker member having a portion thereof coated with paste for engaging a lift in said holder and transferring it to said support.

11. A heel-building machine having, in combination, a lift holder, a support upon which a heel is assembled, a movable picker member for transferring lifts from said holder to said support, means in the path of travel of a portion of said picker member for applying paste to said portion during its movement to said holder, and means for causing said picker member to pass over said paste applying means without engagement during its movement to said support.

12. A heel-building machine having, in combination, a row of lift holders, supporting means upon which heels are assembled, a plurality of concurrently operative picker members for severally transferring single lifts from the respective holders to said supporting means, and a paste-applying roller disposed between said row of holders and

said supporting means for applying paste to the several picker members only during their movement to said holders.

13. A heel-building machine having, in combination, a row of lift holders, supporting means upon which heels are assembled, a paste-applying roller disposed intermediate said row of holders and said supporting means, a plurality of swinging picker arms each having a movable lift-engaging plate associated therewith and adapted to transfer lifts from said holders to said supporting means, said lift-engaging plates being adapted to engage said paste-applying roller in their movement to said holders, and means for causing said plates to engage the lifts in said holders and for subsequently raising said plates and their associated lifts above the plane of said paste-applying roller to prevent engagement therewith during the movement of said picker arms to said supporting means.

14. A heel-building machine having, in combination, a row of holders for stacked lifts of graded characteristics, a plurality of intermittently and independently movable carriers upon which the lifts are progressively assembled, and a plurality of concurrently rotatable picker members, corresponding in number to the component lifts of the heels to be built and acting during periods of rest of said movable carriers for intermittently transferring lifts from the respective holders to the respective carriers in a predetermined sequence.

15. A heel-building machine having, in combination, a row of lift holders, one of which is adapted for rotative movement, supporting means upon which heels are assembled, a plurality of picker members for intermittently transferring lifts from said holders to said supporting means, and means acting between the transferring operations for effecting rotative movements of said rotatable lift holder.

16. A heel-building machine having, in combination, a row of lift holders, one of which is adapted to contain oppositely disposed stacked wedge-lifts, a plurality of movable carriers upon which the lifts are assembled, means for transferring lifts from the respective holders to the respective carriers, and means for intermittently rotating said wedge-lift holder through a predetermined angle.

17. A heel-building machine having, in combination, a row of lift holders, one of which is adapted to contain oppositely disposed stacked wedge-lifts, movable carriers upon which the lifts are assembled, means for transferring lifts from the respective holders to the respective carriers, and means for causing each wedge-lift to occupy the same relative position upon its carrier.

18. A heel-building machine having, in combination, a plurality of lift holders, means tending to feed the lifts through said lift holders, means associated with each holder for clamping the lifts therein, a support for each of the component lifts in the heels to be built, a corresponding number of intermittently operative picker members for concurrently transferring lifts from the respective holders to the respective supports, and means for temporarily releasing said lift clamping means to permit lifts to be fed into positions to be removed by the respective picker members.

19. A heel-building machine having, in combination, a plurality of independent carriers upon which heels are assembled, means for supporting said carriers, and means for periodically engaging said carriers and moving them through predetermined unequal distances.

20. A heel-building machine having, in combination, a plurality of independent carriers upon which heels are assembled, means for intermittently engaging said carriers and moving them through predetermined distances, and means for adjusting the relative positions of said engaging means to vary the lengths of movement of the respective carriers.

21. A heel-building machine having, in combination, a plurality of independent carriers upon which heels are assembled, means for supporting said carriers, reciprocating means having adjustable fingers for engaging and actuating each carrier, and rotatable means having a plurality of spring-pressed fingers for engaging and positioning each carrier against said adjustable fingers.

22. A heel-building machine having, in combination, a plurality of independent movable carriers upon which heels are assembled, means for supporting said carriers, and means periodically engaging the respective ends of each carrier for concurrently actuating them through predetermined unequal distances and arresting them in definite positions.

23. A heel-building machine having, in combination, a plurality of carriers upon which heels are assembled, means for supporting said carriers, means for positively engaging each carrier and concurrently actuating them through predetermined distances, and resilient means cooperating with each carrier for preventing its overshooting its position.

24. A heel-building machine having, in combination, a plurality of independent carriers upon which heels are assembled, means for supporting said carriers and reciprocating means co-operating with each carrier for engaging the carrier, moving the carrier a predetermined distance, disengaging the

carrier, and returning to its initial position, one of said carriers being moved a greater distance than others.

25. A heel-building machine having, in combination, a plurality of independent movable carriers upon which heels are assembled, means for supporting said carriers, a plurality of adjustable spaced fingers, means for moving said fingers into and out of the path of movement of the respective carriers, and means for longitudinally moving said fingers to engage and actuate said carriers through predetermined distances and for returning said fingers to the positions occupied prior to their longitudinal movement.

26. A heel-building machine having, in combination, a plurality of independently movable carriers upon which heels are assembled, and side and middle supporting tracks on which the carriers travel, one end of each carrier being supported upon the side tracks and the other end upon the middle track.

25 27. A heel-building machine having, in combination, a plurality of independent carriers upon which heels are assembled, and means for supporting and actuating said carriers through a plurality of stations and for tilting said carriers at one of said stations relatively to the portion of the carrier support at said station.

28. A heel-building machine having, in combination, a movable carrier upon which heels are assembled, and a plurality of tracks upon which the carrier travels, certain of said tracks being constructed and arranged for tilting said carrier with respect thereto at a point in its travel.

40 29. A heel-building machine having, in combination, a movable carrier normally occupying a substantially horizontal position and upon which lifts are superposed in a plurality of assembling stations, and tracks for supporting and guiding said carrier, one of said tracks having a drop therein to effect an inclination of said carrier in certain of said assembling stations.

30. A heel-building machine having, in combination, a plurality of lift holders, one of which is adapted to contain wedge-lifts, a plurality of normally horizontal independent movable carriers upon which lifts are superposed in a plurality of assembling stations, means for transferring lifts from said holders to said carriers, and means for effecting an inclination of each carrier in its wedge-lift assembling station.

31. A heel-building machine having, in combination, a plurality of lift holders, one of which is adapted to contain wedge-lifts, a plurality of movable normally horizontal carriers upon which lifts are superposed in a plurality of assembling stations, a plurality of inclined tracks for supporting the

front and rear ends of said carriers to provide for the progressive increase of height of the superposed lifts, and means for transferring lifts from said holders to said carriers, one of said tracks being constructed 70 and arranged for dropping the rear end of each carrier as it reaches the wedge-lift assembling station to effect an inclination of the carriers with respect to said tracks to compensate for the tapered character of the 75 wedge-lifts.

32. A heel-building machine having, in combination, a plurality of independent carriers upon which heels are assembled, and side and middle substantially elliptical endless supporting tracks on which the carriers 80 travel.

33. A heel-building machine having, in combination, a plurality of independent carriers, rollers provided at the opposite sides 85 of one end and in substantially the middle of the other end of each carrier, and endless supporting tracks on which the respective rollers travel.

34. A heel-building machine having, in combination, a movable carrier on which heel lifts are assembled, an endless supporting and guiding track therefor, means for adjusting the inclination thereof, and an endless conveyor adjustable with said track 95 for actuating said carrier along a portion of said track.

35. A heel-building machine having, in combination, a plurality of lift holders, a plurality of independent movable carriers 100 upon which lifts from said holders are successively superposed, an inclined supporting track for said movable carriers for accommodating the progressive increase of height of the superposed lifts, means for adjusting 105 the inclination of said track to provide for lifts of different thicknesses and means for intermittently actuating said carriers along said track.

36. A heel-building machine having, in combination, a movable carrier on which heel lifts are assembled, a supporting and guiding track therefor, means associated therewith for tilting said carrier with respect thereto, and means for depositing a 115 wedge lift upon the tilted carrier.

37. A heel-building machine having, in combination, a movable carrier on which heel lifts are assembled, a supporting and guiding track therefor, means for intermittently 120 actuating said carrier through a plurality of assembling stations along said track, and means disposed between certain of said stations for tilting said carrier with respect to said track.

38. A heel-building machine having, in combination, a movable carrier on which heel lifts are assembled, a supporting and guiding track therefor, a continuously operating conveyor, a pivotally mounted mem- 130

ber associated with said conveyor, and means cooperatively engaging said member for causing engagement and disengagement thereof with said carrier along predetermined portions of said track.

39. A heel-building machine having, in combination, a plurality of independent movable carriers on which heel lifts are superposed at a plurality of successive assembling stations, an endless supporting and guiding track therefor, means for actuating said carriers step-by-step through said assembling stations, means adapted to be coated with paste for supplying lifts to the respective carriers, and means for continuously actuating each carrier around the remaining portion of the track.

40. A heel-building machine having, in combination, a plurality of independent movable carriers on which heel lifts are superposed at a plurality of successive assembling stations, an endless supporting and guiding track therefor, means for actuating said carriers step-by-step through said assembling stations, a plurality of concurrently operative pivotally mounted members acting during periods of rest of said step-by-step actuating means for supplying heel lifts one at a time to the respective carriers at their successive assembling stations, and other means for actuating each carrier around the remaining portion of the track.

41. A heel-building machine having, in combination, a plurality of lift holders, a plurality of independent carriers upon which the lifts are successively superposed at a plurality of assembling stations, a plurality of concurrently operative picker members for intermittently transferring lifts from the respective holders to the respective carriers at their respective assembling stations, means for actuating said carriers step-by-step through their assembling stations, means for applying paste to the several picker members prior to their transferring operations, and means for actuating each carrier around the remaining portion of the track.

42. A heel-building machine having, in combination, a series of lift holders, one of which is adapted to contain wedge-lifts, a plurality of movable carriers upon which the lifts are superposed in a plurality of assembling stations, means for concurrently transferring lifts from said holders to said carriers in their several assembling stations, means for concurrently actuating said carriers from one station to another through predetermined distances, and means for causing the actuating distance into the wedge-lift and subsequent assembling stations to be shorter than that into the preceding station, whereby the breast surfaces of the wedge-lift and subsequent lifts are indented with respect to the preceding lift.

43. A heel-building machine having, in

combination, a lift support, means for placing an even lift thereon, means for inclining the support, means for superposing a wedge lift upon said even lift with its breast surface in alignment with the uppermost breast edge of the said even lift, and means for superposing other even lifts upon said wedge lift with their breast surfaces in the plane of the breast surface of said wedge lift.

44. A heel building machine having, in combination, a plurality of lift holders, one of which is adapted for rotative movement, supporting means upon which lifts from said holders are deposited, means for intermittently transferring lifts from said holders to said supporting means, and means acting intermittently for effecting rotative movements of said rotatable holder.

45. A heel building machine having, in combination, a plurality of lift holders, one of which is adapted to contain a stack of wedge lifts arranged in alternate relation, supporting means upon which lifts are deposited, and means for intermittently transferring single lifts from each of said holders to said supporting means, said lift holders and said transferring means being constructed and arranged to cause the transferred and deposited lifts to occupy similar positions with respect to their breast edges.

46. A heel building machine having, in combination, a plurality of lift holders adapted to contain even lifts stacked to an indeterminate height, a lift holder adapted to contain wedge lifts stacked in substantial parallelism to an indeterminate height, supporting means upon which lifts from said holders are deposited, and means adapted to act upon a single lift in each of said lift holders for transferring a series of lifts therefrom to said supporting means.

47. A heel building machine having, in combination, a plurality of lift holders adapted to contain stacks of even lifts, a lift holder of different construction adapted to contain a stack of wedge lifts, supporting means upon which lifts from said holders are deposited, and a plurality of means for transferring single lifts from said holders to said supporting means, the transferring means acting upon the wedge lifts being of different construction from the other transferring means.

48. A heel building machine having, in combination, a rotatable lift holder adapted to contain a stack of wedge lifts arranged in alternate relation, means for periodically picking a lift from the top of the stack and transferring it to a point of delivery, and means for periodically effecting half rotations of said lift holder.

49. A heel building machine having, in combination, a rotatable lift holder adapted to contain a stack of wedge lifts arranged

- in alternate relation, a picker member adapted to periodically move from a position above the lift holder to a position of delivery, means for causing said picker to remove lifts successively from the top of the stack in the lift holder and deposit them at the point of delivery, and means for periodically effecting rotative movements of said lift holder. 5
50. A heel building machine having, in combination, a row of lift holders, one of which is adapted to contain oppositely disposed stacked wedge lifts, supporting means upon which lifts are assembled, means for transferring a series of lifts from the holders to said supporting means, and means for causing the lifts of each series to occupy similar positions upon said supporting means. 10
51. A heel building machine having, in combination, a wedge lift holder adapted to contain wedge lifts stacked in oppositely disposed relation, supporting means upon which lifts are deposited, means for successively transferring lifts from said holder to said supporting means, means for causing said lifts to occupy similar positions upon said supporting means, and means for securing said lifts to previously deposited lifts. 15
52. A heel machine having, in combination, a holder for wedge lifts arranged in a stack with their thick and thin ends alternating, and a movable picker member adapted to engage and remove the endmost lift in said holder, said picker member being self-adjustable to accommodate itself to the inclination of the endmost lift in said holder. 20
53. Blank feeding mechanism having, in combination, a holder for blanks arranged in a stack in alternate relation, and mechanism for seizing the successive blanks in said holder and transferring them to a point of delivery, said holder and said transferring mechanism being relatively rotatable in the plane of the blanks to cause the delivered blanks to occupy similar positions. 25
54. A heel machine having, in combination, a holder for heel lifts arranged in a stack with their breast edges facing alternately in opposite directions, and a picker for acting upon the successive lifts in the holder for transferring them to a point of delivery, said holder and said picker being relatively rotatable in the plane of the lifts to cause the lifts to be delivered with their breast edges facing in the same direction and at an angle to their positions in the holder. 30
55. A heel machine having, in combination, intermittently movable supporting means upon which heel lifts are assembled in superposed relation, a holder for wedge lifts arranged in a stack with their breast edges facing alternately in opposite directions, and a picker mechanism for transferring the lift successively from the stack to said supporting means, said holder and said picker mechanism being relatively rotatable in the plane of the lifts to cause the lifts to be deposited upon said supporting means in similar positions with respect to their breast edges. 70
56. A feed mechanism for tapering articles of sheet material having, in combination, means for holding a stack of such articles with their thick and thin ends alternating, means movable lengthwise of the stack for picking the articles successively from the stack and transferring them to a point of delivery, and means for effecting relative rotatable movements of the holding means and the picking and transferring means in the plane of the articles to cause the articles to be delivered in similar positions with respect to their thick and thin ends. 75
57. A feed mechanism having, in combination, a magazine for holding and advancing a stack of blanks, means acting on the blanks in the stack for normally restraining the advancement of said stack, means for temporarily releasing said restraining means to permit the advancement of said stack, and a movable picker adapted to be positioned adjacent one end of the magazine and to be engaged by the uppermost blank in the stack when the stack is temporarily released and advanced. 80
58. A heel machine having, in combination, means for supporting a stack of lifts and constantly tending to elevate the stack, means acting on the blanks in the stack for normally preventing the elevation of said stack, means for causing the release of said preventing means, and means positioned above the stack at the time it is released and adapted to be engaged by the uppermost lift when the stack is elevated for temporarily limiting the elevation of the stack and successively transferring the uppermost lifts in the stack to a point of delivery. 85
59. Blank feeding mechanism having, in combination, a holder adapted to retain a stack of blanks, means for advancing the stack towards one end of the holder, means for normally clamping said stack to prevent advancement thereof, means for periodically releasing said clamping means to permit the advancement of the stack, and means disposed at the end of the holder and serving as a stop to limit the advancement of said stack, for transferring the endmost blank in the stack to a point of delivery. 90
60. A heel building machine having, in combination, a lift holder adapted to contain a stack of lifts and to periodically advance them towards one end thereof, a movable picker member for transferring lifts 100
65. A heel machine having, in combination, intermittently movable supporting means upon which heel lifts are assembled in superposed relation, a holder for wedge lifts arranged in a stack with their breast edges facing alternately in opposite directions, and a picker mechanism for transferring the lift successively from the stack to said supporting means, said holder and said picker mechanism being relatively rotatable in the plane of the lifts to cause the lifts to be deposited upon said supporting means in similar positions with respect to their breast edges. 105
66. A feed mechanism for tapering articles of sheet material having, in combination, means for holding a stack of such articles with their thick and thin ends alternating, means movable lengthwise of the stack for picking the articles successively from the stack and transferring them to a point of delivery, and means for effecting relative rotatable movements of the holding means and the picking and transferring means in the plane of the articles to cause the articles to be delivered in similar positions with respect to their thick and thin ends. 110
67. A feed mechanism having, in combination, a magazine for holding and advancing a stack of blanks, means acting on the blanks in the stack for normally restraining the advancement of said stack, means for temporarily releasing said restraining means to permit the advancement of said stack, and a movable picker adapted to be positioned adjacent one end of the magazine and to be engaged by the uppermost blank in the stack when the stack is temporarily released and advanced. 115
68. A heel machine having, in combination, means for supporting a stack of lifts and constantly tending to elevate the stack, means acting on the blanks in the stack for normally preventing the elevation of said stack, means for causing the release of said preventing means, and means positioned above the stack at the time it is released and adapted to be engaged by the uppermost lift when the stack is elevated for temporarily limiting the elevation of the stack and successively transferring the uppermost lifts in the stack to a point of delivery. 120
69. Blank feeding mechanism having, in combination, a holder adapted to retain a stack of blanks, means for advancing the stack towards one end of the holder, means for normally clamping said stack to prevent advancement thereof, means for periodically releasing said clamping means to permit the advancement of the stack, and means disposed at the end of the holder and serving as a stop to limit the advancement of said stack, for transferring the endmost blank in the stack to a point of delivery. 125
70. A heel building machine having, in combination, a lift holder adapted to contain a stack of lifts and to periodically advance them towards one end thereof, a movable picker member for transferring lifts 130

- successively from said holder comprising a lift-engaging plate, means for coating said lift-engaging plate with paste, and means for actuating said picker member to bring 5 the coated lift-engaging plate into position adjacent the end of said lift holder at the time when the stack is advanced, whereby the endmost lift is caused to engage and adhere to said coated lift-engaging plate.
- 10 61. A heel machine having, in combination, a plurality of blank holders, supporting means upon which blanks are deposited, means for advancing said supporting means in steps, and a plurality of paste picker 15 members operable at each step for severally taking single blanks from the respective holders and depositing them upon said supporting means.
62. A heel building machine having, in combination, a plurality of lift holders, means for transferring lifts from said holders and assembling them in a superposed pile, and means acting after each lift is deposited upon the pile to engage the upper 25 surface thereof and hold the pile in position while the transferring means is withdrawn.
63. A heel building machine having, in combination, a lift holder, a movable picker member for successively removing lifts from 30 said holder and depositing them at a point of delivery, and independently operated auxiliary means carried by said picker member for stripping each lift from the picker member at the point of delivery.
- 35 64. A heel building machine having, in combination, a lift holder, a movable picker member for engaging successive lifts therein and transferring them to a point of delivery, means for raising and lowering said picker member, stripping means associated with said picker member, and means for actuating said stripping means when the lifts are delivered.
- 45 65. A heel building machine having, in combination, a lift holder, a movable picker member comprising a lift engaging plate for transferring lifts from said holder and depositing them at a point of delivery, means for periodically applying paste to said lift 50 engaging plate, and means operating upon the surface of each lift deposited at the point of delivery for stripping the lift from said lift engaging plate.
- 55 66. A heel building machine having, in combination, a lift holder, a picker member for transferring the lifts successively from the holder to a point of delivery, means for yieldingly depressing the picker member at the point of delivery to deposit the lift, and 60 yieldingly actuated means for stripping the deposited lift from said picker member.
67. A heel building machine having in combination, a support upon which heels are assembled, a lift holder adapted to contain and advance a stack of lifts towards 65
- one end thereof, means for clamping the opposite edges of a portion of the stack to prevent its advancement, a picker member, means for actuating said picker member from a position adjacent the end of the lift holder to a position above said support, means operative when the picker member is adjacent the lift holder for temporarily releasing the stack of lifts and permitting them to be advanced into engagement with 70 the picker member, yielding means operative when the picker member is above said support for actuating said member to deposit the transferred lift, and yielding means for stripping the lift from said picker member, 75 both of said yielding means being adapted to accommodate the progressively increased heights of the heels being assembled.
68. A holder for a stack of blanks having, in combination, a plurality of walls between 80 which the blanks are stacked, a movable supporting follower upon which the stack rests, means tending to urge the follower to raise the stack of blanks, means carried at the upper end of one of the holder walls for resiliently clamping the upper blanks against the opposite wall, and means for releasing said clamping means to permit the stack of blanks to be raised.
69. Blank feeding mechanism having, in combination, a holder having side walls for retaining blanks in stack formation, means for feeding the stack in said holder, a clamping member pivotally mounted at one end of one of said walls and forming an extension 90 thereof, and means for normally actuating said clamping member towards the opposite wall and into firm clamping engagement with the edges of a portion of the blanks to prevent feeding movements of said stack. 95
70. Blank feeding mechanism having, in combination, a holder having side walls for retaining blanks in stack formation, a clamping member pivotally mounted at one end of one of said walls and forming an extension 100 thereof, resilient means carried by the side wall upon which said clamping member is mounted for normally actuating said clamping member into clamping engagement with the edges of a portion of said blanks, and means for releasing said clamping member in opposition to the action of said resilient actuating means. 115
71. Blank feeding mechanism having, in combination, a holder having side walls for 120 retaining a stack of blanks, one of said side walls being pivotally mounted and adapted to be swung towards and from the opposite side wall, means for feeding the stack in said holder, and means for actuating said pivotally mounted side wall to clamp said stack against feeding movements and to subsequently release the stack to permit it to be fed.
72. Blank feeding mechanism having, in 130

- combination, means having side walls for holding blanks in stack formation, a section of one of the walls being movable towards and from the opposite wall, resilient means 5 for normally actuating said section towards the opposite wall and into clamping engagement with the edges of a portion of the stack of blanks to prevent movement of said blanks within the holding means, and means 10 for periodically releasing said wall section from clamping engagement with said blanks.
73. A heel building machine having, in combination, a lift support, means for placing an even lift thereon, means for superposing a wedge lift upon said even lift with its breast surface in alignment with the uppermost breast edge of said even lift, and means for superposing other even lifts upon said wedge lift with their breast surfaces in 15 20 the plane of the breast surface of said wedge lift.
74. Blank feeding mechanism having, in combination, a holder adapted to contain a stack of blanks, and a movable picker member having a blank engaging end incapable of flexure in the plane of the blank constructed and arranged to engage the exposed face of the endmost blank, to accommodate itself to the inclination thereof, and to 25 30 move the blank from the holder.
75. Blank feeding mechanism having, in combination, a holder adapted to contain a stack of blanks, a movable picker member having a blank engaging portion formed 35 wholly of rigid materials, actuating means for causing the picker member to engage the exposed faces of the endmost blanks and remove them successively from the holder, and a self-adjustable connection between said 40 picker member and said actuating means to enable the rigid engaging portion of the picker member to accommodate itself to the inclination of the endmost blank.
76. Blank feeding mechanism having, in 45 combination, a holder adapted to contain a stack of blanks, supporting means, a picker member pivotally mounted thereon and adapted to accommodate itself to the inclination of the endmost blank in the stack 50 55 when brought into engagement therewith, and means for actuating said supporting means to cause the picker to engage the exposed face of the endmost blank and remove it from the holder.
77. A heel-building machine having, in 60 combination, a row of lift holders, supporting means upon which heels are assembled concurrently, said means being inclined from one end to the other to accommodate the progressive increase in height of the heels being built, means for transferring lifts from said 65 70 75 80 85 90 95 100 105 110 115 120 125 holders and depositing them concurrently upon said inclined supporting means, and means for adjusting the position of said inclined supporting means to facilitate building heels of different heights.
78. A heel-building machine having, in combination, a row of lift holders, means for supporting a plurality of heels during their assembly, said means being inclined with respect to said row of lift holders to accommodate the progressive increase in height of heels being built and capable of adjustment in position relative thereto, means for periodically delivering a plurality of lifts, one from each holder, to said supporting means concurrently, and means for actuating the heels being built in steps between the successive operations of said delivering means.
79. A heel-building machine having, in combination, a row of lift holders, means for supporting a plurality of heels during their assembly, said means being inclined with respect to said row of lift holders to accommodate the progressive increase in the height of heels being built and capable of adjustment in position relative thereto, and means for delivering periodically a plurality of lifts, one from each lift holder, to said supporting means concurrently whereby a plurality of heels are progressively built.
80. Blank feeding mechanism having, in combination, a holder adapted to contain a vertical stack of blanks, a picker member movable back and forth between a blank depositing station and a position above said holder and vertically into a position to engage the exposed face of the endmost blank therein, actuating means for said picker, a pivotal connection between said picker and said actuating means to enable the picker to tilt when engaging the blank should the blank be inclined to the horizontal and yielding means for centralizing the picker on its pivot when not engaged with a blank.
81. Blank feeding mechanism having, in combination, a holder adapted to contain a stack of blanks, a movable picker arm, a picker member thereon, actuating means for said arm to place the picker member in position to engage the exposed face of the endmost blank in the holder and remove it from the holder, a connection between the picker member and said arm to enable the picker to tilt and accommodate itself to the inclination of the endmost blank, and means for normally maintaining the picker in an untilted position relatively to the arm.
82. A heel-building machine having, in combination, a horizontal lift carrier, means for placing an even lift thereon, and thereafter a wedge lift on said even lift, and means for tilting the carrier to receive the wedge lift with its upper surface in a horizontal plane.

83. A heel-building machine having, in combination, a plurality of carriers, means for supporting and actuating said carriers step by step through a plurality of lift receiving stations and for successively tilting said carriers at one of said stations, and means for simultaneously depositing a lift on each carrier at each period of rest thereof.
- 10 84. A heel-building machine having, in combination, a plurality of carriers, means for supporting and actuating said carriers step by step through a plurality of lift receiving stations and for successively tilting said carriers at one of said stations, and

means for supplying both even and wedge lifts and depositing them on said carriers, said means being constructed and arranged to supply and deposit a wedge lift at the station at which the carriers are successively tilted.

15 85. A heel-building machine having, in combination, a row of lift holders, an inclined heel support parallel to said row of holders, means for transferring lifts from the holders to said support, and means for adjusting the inclination of said support to facilitate building heels of different heights.

ERASTUS E. WINKLEY.
